UNITED STATES PATENT OFFICE.

PAUL C. DIMBERG, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

METHOD OF MANUFACTURING TURBINES.

Application filed April 9, 1924. Serial No. 705,182.

This invention relates generally to improvements in the art of assembling and permanently uniting elements in predetermined relation to each other, and relates 5 more specifically to an improved method of and means for rigidly connecting a plurality of definitely positioned turbine blades.

An object of the invention is to provide an improved method of uniting turbine 10 blades or the like into segments or complete rings of blades.

Prior to the present improvement, it was ordinary commercial practice to assemble 15 and permanently unite turbine blades into segments, by attaching a shrouded segment to corresponding ends of a plurality of radially disposed blades, and by subsequently attaching a foundation segment to the opposite ends of the blades. The shroud 20 and foundation segments were in some instances attached by fusion of metal, as by brazing, soldering, welding or casting. When casting the foundation segments upon the root ends of the blades, it was customary 25 to use a ramming key to pack the sand adjacent to the blade roots. With such a key it was difficult to obtain smooth passages between the blades of the completed segment, and it was also difficult to secure 30 maximum strength of the blades directly adjacent to the foundation segment.

The present invention contemplates provision of an improved method of uniting the blades into segments, whereby smooth 35 passages between the blades of the completed segment are readily obtainable. The improved method further contemplates provision of means whereby the blades are strengthened at their roots. With the improved 40 method the manufacture of turbine blade segments is also facilitated by eliminating the use of a ramming key, and the cost of production is reduced to a minimum. These and other objects and advantages of 45 the present improvement will be apparent in the course of the accompanying description.

Some of the novel features of turbine 50 blade segment manufacture, disclosed but not specifically claimed herein, form the subject of copending applications.

A clear conception of the various steps of the improved method and of the con-

struction and operation of one embodiment of apparatus which may be used for commercial exploitation thereof, may be had by referring to the drawing accompanying and forming a part of this specification in which like reference characters designate the same or similar parts in the various 55 views.

Fig. 1 is a plan view of a blade assembling jig showing a plurality of blades disposed and clamped therein.

Fig. 2 is a section through the assembling 60 jig of Fig. 1, showing blades assembled and clamped therein.

Fig. 3 is a plan view of a blade segment which has been temporarily but rigidly assembled preparatory to receiving a foundation 70 segment.

Fig. 4 is a section through a core box used for preparing a temporarily assembled blade segment for the reception of a foundation segment.

Fig. 5 is a section through a mold showing a sand packed blade segment disposed therein preparatory to casting a foundation segment thereon.

Fig. 6 is a plan view of a completed blade 80 segment directly after the same has been removed from the mold after casting a foundation segment thereon.

Fig. 7 is a section through a blade segment which has been completely finished 85 and applied to the supporting structure of a turbine.

In the commercial exploitation of the improved method of manufacturing turbine blade segments, a blade assembling jig such 90 as shown in Figs. 1 and 2, is first provided. This jig consists of a segmental bottom plate 10 having a substantially plane upper surface and a curved end surface 12 extending substantially perpendicular to the plane 95 surface; a segmental top plate 6 adapted to be secured to the bottom plate 10 by means of studs 27 and nuts associated therewith and having a resilient blade holding strip 11 attached to the lower face of the overhanging portion thereof; a base strip 100 clamping plate 9 secured to an end face of the bottom plate 10 by means of a series of clamping screws; and a series of radially disposed clamps 8 extending through openings in the bottom plate 10 and having lat-

erally bent outer ends and threaded inner ends cooperable with nuts for adjustment of the clamps. The blades 2 which are adapted to be assembled in the assembling 5 jig, ordinarily have uniform cross sectional area throughout their lengths and are accurately cut to predetermined size with notches 4 in their corresponding longitudinal edges. The shroud segments 3 are 10 ordinarily formed of channel shaped cross section and are notched to receive the adjacent blade ends at the predetermined spacing and angle. The base strip 5 is provided with a series of perforations which are 15 properly spaced and angled to hold the blades 2 inserted therein, in properly spaced and angled position relatively to a shroud segment 3. The perforations in the strip 5 are preferably slightly larger than the 20 blade sections for reasons to be later explained.

When assembling the blades in the assembling jig, the top plate 6 is first released sufficiently to permit insertion of the root 25 ends of the blades between the bottom plate 10 and the resilient strip 11. A base strip 5 may then be clamped against the end surface of the bottom plate 10 with the aid of the clamping plate 9, whereupon the blades 30 2 may be passed endwise through the perforations of the strip 5, the root ends of the blades being brought into engagement with the surface 12 of the plate 10 and being definitely spaced and angled by the perforations 35 of the strip 5. The shroud strip 3 may then be applied to definitely space and angle the outer extremities of the blades, whereupon a filler block 7 may be inserted within the shroud 3 and the clamps 8 applied as shown 40 in Figs. 1 and 2 to positively prevent endwise shifting of the blades. The plate 6 may then be forced into clamping position with the aid of the nuts and studs 27, causing rigid clamping of the blades 2 and the 45 strips 3, 5 within the jig. While the blades 2 and the associated elements are thus positively held in properly spaced and angled position, the shroud strip 3 may be rigidly and permanently attached to each of the 50 blades by brazing, welding, soldering or otherwise. The base strip 5 may also be rigidly locally attached to several of the blades 2 as indicated at 13 in Fig. 3, by brazing, welding, soldering or the like. When 55 the shroud and base strips 3, 5 have been thus permanently attached to the blades, the blades 2 are rigidly united to produce a unitary segment and may be removed from the assembling jig upon release of the top plate 6, clamping plate 9 and clamps 8. The work of temporarily assembling and uniting the blades 2 into segments may be accomplished by experts in this particular art, and the assembling jig may be utilized to rapidly 60 assemble successive segments.

The temporarily but rigidly united blade segments consisting of the radially disposed properly spaced and angled blades 2, the shroud segment 3, and the base strip 5, shown in Fig. 3, may then be transferred to 70 the foundry being ready to receive the permanent foundation segment. In the foundry, each segment must first be prepared for casting. For this purpose a core box such as shown in Fig. 4 is provided, the core box 75 consisting of a bottom section 15 and a top section 14, these sections being provided with an intervening space adapted to conveniently receive a temporarily assembled blade segment. Each temporarily assembled 80 blade segment is first placed in the recess of the lower section 15 of the core box and the space between the successive blades 2 and between the shroud and base strips 3, 5 is completely filled with sand 16, the sand being well packed into this space. The top section 14 is then applied to produce a core 85 of definite size, whereupon the sand packed segment is ready for insertion in a mold.

With the aid of a suitable pattern, a mold 90 such as disclosed in Fig. 5 is then provided, the mold consisting of a cope 17 and drag 18 having a gate 19 communicating with a segmental space 20. With a sand packed blade segment inserted within the mold as shown 95 in Fig. 5, the segmental space 20 surrounds the root ends of the blades 2 which project beyond base strip 5. The gate 19 is preferably located intermediate the ends of the segmental space 20 so that the metal is not undesirably chilled before it reaches the extreme ends of this space. The metal is poured through the gate 19 to the space 20 and completely surrounds the projecting root ends of the blades 2 and fuses with these 100 blade ends as well as with the exposed surfaces of the strip 5. By virtue of the fact that the perforations in the strip 5 are made slightly larger than the cross sections of the blades 2, the metal also passes through the space between these perforations and the blades 2 and travels a slight distance along the blades to form a fillet at each blade 2 where it enters the strip 5. During the casting 105 operation, the strip 5 expands slightly, but the strip is returned to normal condition during cooling and shrinkage of the casting.

The blade segment with the foundation 110 segment 21 attached thereto by fusion of metal after removal from the mold, is shown in Fig. 6, this segment being ready to receive a bracing or lacing strip 26 which is applied in the notches 4 and is attached to the blades 115 in any suitable manner as by brazing, welding or soldering. With the segment thus completed, the same is ready for final finishing preparatory to application thereof in a turbine. The finishing of the segment is accomplished in any convenient manner, the 120 125 130

finished segment being provided with a segmental groove 23 and in some instances having one side of the channel shaped shroud 3 bent as indicated at 25. The groove 23 is 5 adapted to coact with a tongue formed on a supporting element 22, proper coaction between the tongue and groove being maintained by means of a calking strip 24 as shown in Fig. 7.

10 It has been found that the base strips 5 provide absolutely smooth passages between the blades 2 adjacent to the foundation segments 21. These strips 5, besides properly spacing and angling the blades, also provide 15 relatively greater strength for the blades 2 at their root ends, where strength has been found essential. The use of the base strips 5 also facilitates manufacture of the segments by eliminating the use of ramming tools for packing the sand, and permits 20 formation of the steam passages of any desired shape, depending upon the shaping and disposition of the strips 5. It has also been found that the strips 5 may be readily 25 attached to the foundation segments 21 by fusion of metal, such fusion being accomplished by selecting proper materials for the strips 5 and the foundation segments 21. It will be obvious that elements other than 30 turbine blades may be readily assembled and united with the aid of the present improvement, to produce a more efficient assemblage of such elements at minimum cost of production.

35 It should be understood that it is not desired to limit the invention to the exact steps of the process and to the exact details of construction and operation of the apparatus herein shown and described, for various 40 modifications within the scope of the claims may occur to persons skilled in the art.

It is claimed and desired to secure by Letters Patent:

1. The method of assembling turbine 45 blades, which comprises, providing a strip having perforations slightly larger than the cross-sectional area of the blades, assembling the blades in said strip, permanently attaching a shroud to corresponding ends of 50 the blades, and casting a foundation segment around the root ends of the assembled blades and in the space between said perforations and said blades.

2. The method of assembling turbine 55 blades, which comprises, providing a segmental strip with perforations slightly larger than the cross-sectional area of the blades, assembling the blades in said strip and permanently attaching said strip to 60 some of said blades, permanently attaching

a shroud segment to corresponding ends of the blades, and casting a foundation segment around the root ends of the assembled blades and in the space between said perforations and said blades.

3. The method of assembling turbine 65 blades, which comprises, providing a perforated strip of proper dimensions, assembling a plurality of blades in the perforations of said strip, permanently attaching some of 70 said blades only to said strip at said perforations, permanently uniting the ends of all of said blades remote from said strip, and casting a foundation segment around the root 75 ends of said blades and in contact with said strip.

4. The method of assembling turbine 80 blades, which comprises, providing a perforated strip of proper dimensions, assembling a plurality of blades in the perforations of said strip, permanently uniting the ends of 85 said blades remote from said strip by attaching a shroud strip thereto, and casting a foundation segment around the root ends of said blades and in contact with said strip.

5. The method of assembling turbine 90 blade segments, which comprises, providing a perforated segmental strip, assembling a plurality of blades in the perforations of said strip, brazing a shroud segment to the 95 ends of said blades remote from said strip, permanently attaching said strip to some of said blades only, and casing a foundation segment around the root ends of said blade and in contact with said strip.

6. The method of assembling turbine 100 blade segments, which comprises, providing a perforated segmental strip, assembling a plurality of blades in the perforations of said strip, permanently attaching a shroud 105 segment to corresponding ends of the blades, permanently attaching the perforated strip to some of the blades, and casting a foundation segment around the root ends of the blades and in direct contact with said strip.

7. The method of assembling turbine 110 blades, which comprises, permanently uniting corresponding ends of a plurality of blades by attaching a shroud strip thereto, applying the blades adjacent to their root 115 ends to the perforations of a base strip, casting a foundation segment around the root ends of the base and in contact with said base strip, and subsequently attaching a calking strip to said blades intermediate their ends.

In testimony whereof, the signature of the inventor is affixed hereto.

PAUL C. DIMBERG.
